COMBINED BENCH AND TABLE

Charles O. Larson, Sterling, Ill.

Application November 27, 1944, Serial No. 565,330

2 Claims. (Cl. 155—43)

1

This invention relates to a bench and table combination.

One of the objects of the present invention is to provide a knockdown bench and table combination comprising two benches, each provided with a seat and supporting legs and a pair of uprights and a back hingedly connected to the uprights at points intermediate the width of the back end in such a manner that the back may be shifted from a substantially vertical position where it acts as a back for the seat, to a substantially horizontal position where it functions as a table top, there being means for holding the back in such horizontal position.

Another object of the invention resides in providing a pair of such benches which may be disposed in spaced apart relation and pivotally connected intermediate their tops and bottoms to uprights so that when the backs are shifted to horizontal position their inner edges will be confronting and contiguous, and held so by means carried by the backs of each pair of benches whereby they may be locked with their edges in confronting, contiguous relation.

Another object of the invention is to provide a continuous table top between the benches, the width of which is equal to twice the width of the backs.

Yet another object of the invention resides in providing a bench having a shiftable back which is pivotally mounted between the uprights to one side of the central axis of the back so that the greater weight of the longer portion or heavier half of the back will normally cause the back to swing to substantially vertical position, whereby the same acts as a back, but which can be shifted to horizontal position and locked in such position to provide a table top.

Yet another object of the invention resides in providing a knockdown bench of the foregoing character wherein the legs, the back, and the uprights can be quickly dismantled for storage purposes.

Another object of the invention is to provide the foregoing type of bench, wherein the back is detachable as one piece and the two legs are removable from the seat, leaving the seat intact, and wherein all four sections may be stacked in a small space.

Another object of the invention is to provide a

2

bench of the foregoing character wherein the back is pivoted to uprights carried by the bench so that the back may swing slightly in sitting position to accommodate the back of the sitter.

Yet another object of the invention resides in providing a bench composed of pre-cut timbers and hardware clamps, wing nuts, bolts and hooks, arranged so that the entire bench may be assembled very quickly from the pre-cut forms and the hardware.

Other and further objects of the invention will be apparent from a perusal of the following specification, when taken in connection with the accompanying drawing, wherein:

15 Figure 1 is an assembled view of two of the benches arranged to provide a common table top which serves as a rigid interconnection between the two benches;

20 Figure 2 shows the two benches, each with its back swung down to back supporting position for the bench;

Figure 3 is a rear view of one of the backs;

Figure 4 is a vertical sectional view of the design shown in Figure 1;

25 Figure 5 is a view taken on the line 5—5 of Figure 4;

Figure 6 is a side view of the bench and the back support as a table top; and

30 Figure 7 is a view of the manner of placing the eye for holding the table top in horizontal position.

Referring now to the drawings in detail, each bench comprises two pairs of feet, the same being parallelly arranged boards 2 and 4 spaced apart to receive two upstanding legs 6 and 8, the latter in the form of an inverted V, and to receive therebetween an inclined upright 10. It will be understood that these uprights are arranged in pairs, one at each end of the bench. Suitable bolts and wing nuts 12, 14 and 16 serve to hold the two legs 6 and 8 and the upright 10 between the feet 2 and 4. This construction is duplicated at each end of the bench. The hardware clamp 18 is provided at each end of the legs 6 and 8 for holding them in assembled position, as shown in Figure 4. To this end the upper ends of the legs 6 and 8 are cut along the line 20 which is a line formed at an angle to the inner converging walls 21 and 22 of the legs 6 and 8. The tops of the legs 6 and 8 are cut off so that

they lie in a common plane and the hardware clamp 18, formed of sheet metal, embraces the common assembled sides of the two legs 6 and 8, as shown in Figure 5, and has a flange 23 which embraces the narrower side of each one of the legs 6 and 8, as shown clearly in Figure 1. Suitable screws 24 and 26 pass through the hardware clamp 18 into each of the legs. In addition, a horizontal brace 28 is bolted to the inner faces of the tops of the legs 6 and 8, as shown in Figure 5, the bolt 30 passing therethrough and through the clamp 18 and being held in secure position by the thumb nut 32. This horizontal extension brace 28 projects outwardly at one side of the bench, as shown at 36 in Figure 4, and connects by means of a bolt and wing nut 38 to the upright 10 to support the upper end of said upright.

Each bench has a top 42 which overlies the junction of the upper portion of the legs. This top is secured in position by bolts 44 which pass downwardly through the top and through a flange 46 on the hardware, being held in secured position by thumb nuts 48. There are two of these bolts 44 which pass downwardly through the central end portions of the bench top 42 and engage the broad flange 46 of the hardware, as shown in Figures 4 and 5. In addition, right angled base fittings 50 are fastened to the underside of the top 42 and to the upper vertical side of the horizontal brace 36. This forms a rigid connection between the bench top 42 and its horizontal brace 36. Both ends of the bench are constructed similarly.

A combination back and table top is provided for the upper portion of each bench. Each back comprises preferably a pair of boards 52 and 54, or if desired a single board of the same width, and each pair of boards is held together by a transverse rigidifying member 56 which may be made either of metal or wood, but preferably wood. The two boards are rigidly secured to the cross member 56 by means of the L-shaped or right angled fittings 58 which are secured by screws in each angular leg thereof as at 60 and 62 to the transverse member 56 and to the table top. The transverse member 56 is provided with a horizontal bore at one side of its center and a pivot pin 64 in the form of a bolt passes therethrough and through a registering aperture in the top of the upright support 10 to form a pivotal connection. Wing nut 65 serves to hold the back in pivoted position but permits it to swing so that its heavier end 66 will automatically shift downwardly to the dotted line position shown in Figure 4. The underside of the cross bar support 56 is provided at each end with an eye screw 68 to receive an elongated hook 70 pivoted as at 80 to the upright 10. The hook 70 is preferably an eight inch hook and its end lockingly engages the eye 68 to hold the back 66 in horizontal position. It is understood that only one hook positioned at either end of support 56 need be used.

In addition, each back is provided with either an eye 82 or one may be provided with an eye 82 and the other with a pivotal hook 84. When two of the benches are placed in the spaced position shown in Figure 4 and the backs 66 are shifted to horizontal position and locked in such position by the hooks 70, the confronting edges of the table tops will be contiguous, as shown in Figure 4, so as to form a continuous table top of double the width. In this position the tops may be locked between hook and eye 82 and

84, which thus maintains them in contiguous relation.

When it is not desired to use the table top the hooks 70 and 84 are released, whereupon the back 66 will automatically swing downwardly to the dotted line position.

It is to be noted that in a sitting position the back 66 by reason of its pivotal mounting may swing slightly toward and away from the supporting uprights 10, which thus accommodates the back of the sitter and is of considerable advantage and use.

Furthermore it will be noted that the back may be removed from its uprights 10 as one single piece, this being done by removing the wing nut 65 and removing the bolts. It will be further noted that when the fittings 50, which if desired may interconnect the table top with the upper portion of each of the legs, are not desired to be used, simply by removing the bolts 44 and the bolts 30 the legs 6 and 8 may be removed from the bench seat and by removing the bolts 12 and 14 the bottom feet may be removed for storage purposes.

It will thus be seen that by providing the necessary precut lumber to form the seats, the legs, the feet of the uprights, and the backs, and by providing four pieces of the hardware clamps 18 and a sufficient number of L-shaped rigidifying fittings 50, together with bolts, screws, wing nuts and the hooks, I provide a complete knock-down set which may be shipped to the point of use and there assembled for instant and ready use.

Obviously the invention is not limited to the specific details of construction disclosed herein but is capable of other modifications and changes without departing from the spirit and scope of the appended claims.

Having thus described the invention, what I claim as new and desire to secure by Letters Patent is:

1. A bench comprising two feet, each composed of a pair of parallel horizontal strips of lumber, a pair of inverted V-shaped legs having their bottoms detachably connected therebetween by bolts and wing nuts, a sheet metal clamp surrounding the converging upper ends of said legs and bolted thereto to hold the same together, a horizontal cross support interconnecting said upper portions of said legs and projecting at one end outwardly beyond said legs, a board bench top bolted to a horizontal flange of said clamp, rigidifying L-shaped braces interconnecting the underside of said bench top and the side of said horizontal brace relatively, a long upstanding bar pivotally connected between said pair of parallel strips and connected to said horizontal cross support, and a back member having cross supports at its end perforated to form a pivotal axis, and a bolt passing through each back cross support held by a wing nut forming a pivotal support, said support being to one side of the center of the back, whereby said back is adapted to swing down to vertical position, said back being shiftable to horizontal position, and means to maintain said back in said horizontal position.

2. In a combined table and bench assembly a pair of benches adapted to be spaced apart a predetermined distance, each bench having two pairs of inverted V-shaped legs, a pair of sheet metal clamps, one surrounding the converging upper ends of each pair of legs and bolted thereto to hold the same together, a pair of horizontal cross supports, one interconnecting the upper portions of each pair of legs and projecting at

one end outwardly beyond said legs, a bench top bolted to horizontal flanges on each of said sheet metal clamps, a pair of bars extending upwardly at an angle, one at each end of said bench, means connecting the lower ends of said bars to said legs and means connecting the mid-
portions of said bars to said horizontal cross supports, a back member pivoted intermediate its width to said pair of bars at their upper ends whereby said back is pivotable from a substantially vertical position on said bars to a horizontal position, and means carried by each back for interlocking it with the back of the other of said pair of benches in contiguous and juxtaposed horizontal position to form a substantially continuous table top with the seats disposed below and parallel to an outside edge of the table top.
